FIG. 3.

UNITED STATES PATENT OFFICE.

FRANK ARTHUR BOOLE AND LEONARD DEE STEPHENSON, OF BLAINE,
WASHINGTON.

CAR.

No. 844,915.

Specification of Letters Patent.

Patented Feb. 19, 1907.

Application filed December 16, 1905. Serial No. 292,019.

To all whom it may concern:

Be it known that we, FRANK ARTHUR BOOLE and LEONARD DEE STEPHENSON, citizens of the United States, and residents of Blaine, in the county of Whatcom and State of Washington, have invented a new and Improved Car, of which the following is a full, clear, and exact description.

Our invention relates to cars, and especially to those for holding lumber in kilns during process of drying. Its principal objects are to provide such a car in which each piece of lumber will be separated from those adjacent to it by an air-space and which may be readily assembled or disassembled.

Reference is to be had to the accompanying drawings, forming a part of this specification, in which similar characters of reference indicate corresponding parts in all the figures.

Figure 1 is an end elevation of one embodiment of our invention. Fig. 2 is a longitudinal section on the line 2 2 of Fig. 4. Fig. 3 is a side elevation of the car, and Fig. 4 is a horizontal section on the line 4 4 of Fig. 1.

The numeral 10 indicates an ordinary dry-kiln truck, its wheels 11 being adapted to run upon rails, (indicated at 12.) Two or more of these trucks support a base consisting of beams 13, here shown as two in number and carrying sills 14, which may vary in number according to the length of the lumber to be supported, there being three here illustrated. Each of the sills is shown as reinforced upon its upper face by a channel-iron 15.

Extending upwardly from opposite sides of one extremity of each of the sills is a retaining member 16, and between these bars or retaining members is supported an upright, including a bar 17, having at its inner side a facing 18, furnished by a channel-iron. Straps 19, fixed to the retaining members, surround each upright to hold it in place upon its sill. In the inner face of each of the bars

17 is a vertical series of depressions 20, in registration with which are openings 21 through the channel-irons 18, these openings being at the upper portion of the depression and furnishing at the lower portion a chamber 22 closed save at its upper extremity. With these depressions and openings coöperate hooked and engaging portions 22 of supporting members 23, conveniently furnished by channel-irons having their flanges extending

downwardly. The engaging portion is of such width that each support is held against lateral movement in the opening 21, while the contact of the hooked end, which projects into the chamber, retains the support against longitudinal movement.

The supports beyond the uprights are separated from their sill and from one another by tubular spacing members 24, which may consist of sections of pipe located between the ends of the elements and extending upwardly. They are shown as secured in place by bolts 25, the head 26 of each engaging the upper extremities of the tubes, while the shanks pass downwardly through openings in the supports and are threaded to receive the nuts 27. The length of the member 24 is such that the supports are maintained in parallelism with one another at right angles to the uprights. To sustain their outer ends, each support and also the sills have tubular spacing members 28, plugged at 29. In the plug of each of these members is a bore to receive a bolt 30, which extends downwardly through the support or sill and is secured by a nut 31. The length of the plug is such that a recess is left at the upper extremity of the members 28. When the elements are assembled this recess receives the head of the securing-bolt above it. Thus the outer ends of the supports are held against lateral play. Rising from each sill and support between the upright and supporting members are series of projections 33, which may be furnished by sections of pipe of less diameter than the separating members, secured in place by bolts 34 and nuts 35 in the same manner as has been described in connection with the members 24. The length of the projections 33 is preferably somewhat less than the separating members, so that spaces are left between them and the flanges of the supports.

In using our improved car a base is built up by employing the desired number of trucks, beams, and sills and uprights of such a length as to give the requisite holding capacity, applied as has been previously described. The supports, bearing the separating members and projections, are then placed one upon another until the car is completed. The pieces of lumber indicated at A may now be inserted between the separating members and projections and when thus placed are

entirely free from contact with one another, they being surrounded by a free air-space, save of over the widely-separated and contracted portions where they contact with the supports and other extensions. When the car and its load is within the kiln, this arrangement insures a quite uniform drying, and by using slow heat at the start the perfect circulation secured will approximate air-drying, escaping the usual deterioration present in kiln-drying. In addition it will be seen that the structure admits of being readily built up to meet the requirements of any particular case and as easily knocked down for storing away or transportation.

Having thus described our invention, we claim as new and desire to secure by Letters Patent—

1. A car comprising a base, spaced uprights secured to one side of the base, a vertically-spaced series of supports detachably connected with each of the uprights, spacing members connected to the free end of each support, and adapted to engage the overlying support, and a spacing member for the free end of the lowest support secured to the base.

2. A car comprising a base, spaced uprights secured to one side of the base, a vertically-spaced series of supports detachably connected with each of the uprights, spacing members connected to the free end of each support, and adapted to engage the overlying support, a spacing member for the free end of the lower support secured to the base and spaced projections upon each of the supports and upon the base, said projections being of less height than the spacing members.

3. A car comprising a base, spaced uprights secured to one side of the base, a vertically-spaced series of supports, detachably connected with each of the uprights, spacing

members connected to the free end of each support, for engaging the overlying support, a spacing member for the free end of the lower support secured to the base, and means in connection with the spacing members and supports for preventing lateral movement of said supports with respect to said spacing members.

4. A car comprising a base, spaced uprights secured to one side of the base, a vertically-spaced series of supports detachably connected with each of the uprights, spacing members connected with the supports, and a spacing member for the lower support connected with the base.

5. A car comprising a base, an upright having openings, supports provided with hooked portions for engagement with the upright-openings and means of separating supports at points removed from the uprights.

6. A car comprising a base, an upright, supports connected with the upright and having projections, and tubular members fixed to the supports and having recesses for coöperation with the projections upon an adjacent support.

7. A car comprising a base, an upright, bar having depressions, a channel-iron situated at one side of the bar and having openings registering with the depressions, supports provided with portions coöperating with said openings and depressions and also having series of projections.

In testimony whereof we have signed our names to this specification in the presence of two subscribing witnesses.

FRANK ARTHUR BOOLE.
LEONARD DEE STEPHENSON.
